A. P. DRAPER

GAME

Filed Feb. 18, 1922

Patented Jan. 1, 1924.

1,479,460

UNITED STATES PATENT OFFICE.

ARTHUR P. DRAPER, OF LEBANON, MISSOURI.

GAME.

Application filed February 18, 1922. Serial No. 537,432.

To all whom it may concern:

Be it known that I, ARTHUR P. DRAPER, a citizen of the United States, residing at the city of Lebanon, county of Laclede, and State of Missouri, have invented a certain new and useful Improvement in Games, of which the following is a full, clear, and exact description, such as will enable others skilled in the art to which it appertains to make and use the same, reference being had to the accompanying drawings, forming part of this application.

This invention relates to games, and more particularly to baseball games.

The objects of my invention are: to provide a game of the class described which is inexpensive to manufacture, can be easily operated and readily understood, and which will as closely as possible approximate the plays of the actual game.

Further objects of my invention are to provide a game having means which when actuated will project or discharge a suitable member onto a board having a plurality of play-indicating marks whereby the progress of the play is determined by the mark on which said projected member comes to rest.

Still further objects of my invention are to provide a game board having a plurality of play-indicating marks arranged thereon, which marks are divided into groups, each group being referable to a certain player and the marks of each group being in co-operative relation with the marks of the remaining groups whereby when a mark of one group is selected to indicate the fate of a player at bat, those marks of the remaining groups which are in co-operative relation or alinement with the selected mark are used to determine movements or fates of the other players.

With these and other objects in view, my invention consists in certain novel features of construction and arrangements of parts hereinafter more fully described and illustrated in the accompanying drawings, in which—

Figure 1 is a plan view of the game.

Figure 2 is a vertical cross-section taken on line 2—2 of Figure 1.

Figure 3 is a perspective detail view of a member designed to be projected onto said board.

Figure 4 is a detail view of a miniature bat used to actuate the projecting means.

Figure 5 is a detail view of one of the counters or play recording objects.

Referring by numerals to the accompanying drawings, 10 indicates a board preferably reinforced by a frame 10^a, and provided on its upper face with a marked portion 11. This marked portion 11 is divided longitudinally by lines 12 into four columns 14, marked "A," "B," "C" and "D," respectively. And each column is marked at the top and bottom to indicate its reference to certain players. The marks at the tops of the columns govern the fielding players; column A being marked "First baseman Right fielder"; column B, "Second baseman Center fielder"; column C, "Pitcher Short stop"; column D, "Third baseman Left fielder." The marks at the bottom of each column indicate the batting team or players, as follows: column A "Batter;" column B, "Runner on first;" column C, "Runner on second" and column D, "Runner on third." The portion 11 is also provided at suitable intervals with a plurality of transverse lines 15 which intersect at right angles lines 12 and divide each column into spaces 16.

Lines 15 and spaces 16 are suitably marked to indicate possible plays and, preferably, probable plays of the actual game. The marks 15 and 16 of each column or group are in horizontal alinement or cooperative relation with the marks of the remaining columns, so that when playing the game, a mark in one column is selected in any suitable manner, such as by projecting an object onto the marked portion 11. Those marks on the remaining columns which are in horizontal alinement or cooperative relation with the selected mark are used to determine the movements or fates of such players on the batting side as are occupying the bases. These cooperating marks are referable to the players by means of the marks placed at the top and bottom of each column 14.

Suitably located on face 11 are comparatively large circles 17 marked "Home run" and smaller circles 18, marked "3 base hit." A diamond 19 having the usual home plate and base plates is arranged on face 11 adjacent to the forward end of the board and in a central position with respect to columns 14. A projecting or discharging member 20, having depending side portions 21, is pivotally mounted by means of pins or rivets

22 on the upwardly presented lugs or ears 23 of plate 24, which latter is fixed to the board 10 forwardly of the home plate of diamond 19. This projecting member or lever 20 is unbalanced so that its ends which is remote from the marked face 11 is depressed and rests on board 10.

A suitable pocket or seat 25, formed by pressing upwardly the marginal portion, is arranged on the lever 20 for the reception of a flat disk 27 which in the present instance represents a baseball, and this disk is designed to be used as the play indicating or determining member.

15 A series of markers or counters 28, preferably representing players in action, is provided with each game, and the markers are arranged to be placed in the proper position on the diamond in order to indicate and record the progress of the game. Lever 20 is 20 preferably actuated by means of a bat 29 which is used to strike the raised end of lever 20, thus actuating the latter on its pivots 21 and causing its depressed end to move upwardly and discharge disk 27 onto 25 the marked field or face 11.

In operating my game apparatus, the rules of the regular game are followed. In the present instance, the game apparatus is 30 designed for use as a baseball game, and the counting of strikes, balls, etc., is done in accordance with the rules controlling the regular baseball game.

In playing the game, the player places disk 27 in the seat 25 of lever 20. The player then actuates said lever by tapping or striking sharply the raised end thereof with his finger, or, preferably, by means of the bat 29. This causes the depressed end 40 having pocket 25 to move upwardly and discharge disk 27 which is projected outwardly and falls on the marked face or field 11 of the board 10. The mark of one of the lines 15 or one of the spaces 16 or circles 17 or 18 at which the disk comes to rest determines the play. For instance, if the disk 45 occupies one of the spaces marked in column A, "1 base hit" the player places one of the counters 28 on the first base of diamond 19.

50 If there was a runner on the first base, by consulting that mark of column B which is opposite to or in cooperative relation with the mark "1 base hit" on column A, it will be noted that this space is marked "Advance".

55 indicating that the runner is to be advanced to second base, while the batter is moved to first base. Suppose in the next operation, disk 27 comes to rest in a space marked under column A "2 base hit".

60 der column A "2 base hit." By examining column B, it will be found that the space registering with mark "2 base hit" marked "Caught at plate;" consequently the runner

at first base is out. By examining column C, it will be noted that the space aligned with the mark "2 base hit" is marked "Score."

Therefore, the runner who was occupying the second base scores, and the batter in accordance with the mark "2 base hit" is then moved to second base. Suppose, further, that with the bases full, the ball or disk falls on a certain line marked under column A "Ball." This means one ball in the batter's favor. By examining the columns, it will be found that under column B the runner on first holds his base, under column C, the runner on second was "caught napping," and in column D, it will be noted that the runner on third holds his base. The point being that each projection of the ball or disk 27 onto the field 11 affects any player indicated in the particular column governing his movement or fate; and if there is no player, no attention is paid to the column governing same.

In the matter of accepts and errors by the fielding team, the column the disk comes to rest in decides who gets the credit or the blame. If it is an outfield play, the column indicates what outfielder made the play. If an infield play, the column shown which infielder made the play. A ball or disk resting on one of the longitudinal lines counts for the pitcher. 85 90 95 100

My improved game is light in weight, occupies very little space, and can be manufactured at a small cost. 95

While I have shown and described the preferred form of my invention, it is obvious that various changes in the size, shape and arrangements of marks could be made 100 and substituted for those herein shown.

What I claim is:

1. A game comprising a board provided with a plurality of play directing marks arranged in parallel groups, individual marks arranged on said board adjacent to each group whereby each group is referable to a definite player, there being a playing field of conventional baseball form arranged on said board and containing a plurality of stations whereon a plurality of players are operatively associated, play-recording counters arranged to be placed on said field in accordance with the progress of the play, a lever pivotally mounted on said board and having one end provided with a seat, and a flat member adapted to be placed on said seat, whereby when said lever is actuated said flat member is discharged onto said board and the play is determined in accordance with the mark at which said member comes to rest.

2. A game comprising a board provided with a plurality of play directing marks arranged in groups, said groups being arranged in parallel rows, individual marks adjacent to each group whereby each group is referable to a definite player, a series of spaces arranged on said board independently of said groups, and provided with cer- 130 125

tain other play directing marks, a playing field of conventional baseball form on said board arranged centrally with respect to said groups and containing a plurality of 5 stations whereon a plurality of players are operatively associated, a plate fixed on said board adjacent to said playing field and said play directing marks and provided with upwardly projecting lugs, a lever pivotally supported on said lugs and provided with an

upwardly projecting marginal flange to form a seat, and a disk adapted to be placed on said seat and designed when the lever is actuated to be discharged onto said board whereby the play is determined by the 15 mark at which the disk comes to rest.

In testimony whereof I hereunto affix my signature this 18th day of February, 1922.

ARTHUR P. DRAPER.
